US0D1111633S

(12) **United States Design Patent** (10) **Patent No.:** **US D1,111,633 S**
(45) **Date of Patent:** **** Feb. 10, 2026**

(54) **OVEN**

(71) Applicant: **OONI LIMITED**, West Lothian (GB)

(72) Inventors: **Gavin Klocek**, Edinburgh (GB);
Eduardo Garcia Valdes, Coruna (ES);
Matti Kristian Tapaninaho, Edinburgh (GB)

(73) Assignee: **OONI LIMITED**, Broxburn (GB)

(**) Term: **15 Years**

(21) Appl. No.: **29/973,646**

(22) Filed: **Nov. 18, 2024**

(58) **Field of Classification Search**

CLAIM

The ornamental design for an oven as shown and described.

DESCRIPTION

The patent or application file contains at least one drawing executed in color. Copies of this patent or patent application publication with color drawing(s) will be provided by the Office upon request and payment of the necessary fee.
FIG. 1 is a perspective view of a first embodiment of an oven from above and left;
FIG. 2 is a front view thereof;
FIG. 3 is a rear view thereof;
FIG. 4 is a right view thereof;
FIG. 5 is a left view thereof;
FIG. 6 is a base view thereof;
FIG. 7 is a top view thereof;
FIG. 8 is a perspective view of a second embodiment of an oven from front and right with door closed;
FIG. 9 is a front view of the second embodiment of the oven with door open;

FIG. 10 is a rear view thereof;
FIG. 11 is a right view thereof;
FIG. 12 is a left view thereof;
FIG. 13 is a top view thereof;
FIG. 14 is a perspective view of the second embodiment of the oven from front and right with door open;
FIG. 15 is a perspective view of the second embodiment of the oven from front and left with door closed;
FIG. 16 is a base view thereof (in which a handle of the oven is not shown due to the camera angle);
FIG. 17 is a front view of the second embodiment of the oven with door closed;
FIG. 18 is a perspective view of a third embodiment of an oven from front and left with door closed;
FIG. 19 is a front view of the third embodiment of the oven with door open;
FIG. 20 is a rear view thereof;
FIG. 21 is a right view thereof;
FIG. 22 is a left view thereof;
FIG. 23 is a base view thereof (in which a handle of the oven is not shown due to the camera angle);
FIG. 24 is a top view thereof;
FIG. 25 is a perspective view of the third embodiment of the oven from front and right with door closed;
FIG. 26 is a perspective view of the third embodiment of the oven from front and right with door open;
FIG. 27 is a front view of the third embodiment of the oven with door closed;
FIG. 28 is a perspective view of a fourth embodiment of an oven from front and right with door closed;
FIG. 29 is a front view thereof;
FIG. 30 is a rear view thereof;
FIG. 31 is a right view thereof;
FIG. 32 is a left view thereof;
FIG. 33 is a base view thereof (in which a handle of the oven is not shown due to the camera angle);
FIG. 34 is a top view thereof;
FIG. 35 is a perspective view of the fourth embodiment of the oven from front and left;
FIG. 36 is a perspective view of a fifth embodiment of an oven from front and left;
FIG. 37 is a rear view thereof;
FIG. 38 is a right view thereof;
FIG. 39 is a left view thereof;
FIG. 40 is a base view (in which a handle of the oven is not shown due to the camera angle);
FIG. 41 is a top view thereof;
FIG. 42 is a perspective view of the fifth embodiment of the oven from front and right; and,
FIG. 43 is a front view thereof.
The broken lines and the area within them form no part of the claimed design.
